GROCERY BAG PACKER

Ray F. Shores, 3 Venus Court,
Baltimore, Md. 21234

Filed Jan. 27, 1969, Ser. No. 15,505

Term of patent 14 years

Int. Cl. D6—01

U.S. Cl. D80—1

FIG. 1 is a perspective view taken from the front and one side of a grocery bag packer showing my new design; and

FIG. 2 is a perspective view taken from the rear and side opposite that shown in FIGURE 1.

The broken line representation of a six-pack in FIGURE 1 and the fragmentary broken line showing of a check-out counter in FIGS. 1 and 2 are for purpose of illustration only.

I claim:

The ornamental design for a grocery bag packer, as shown and described.
